UNITED STATES PATENT OFFICE.

GEORG WESENBERG, OF ELBERFELD, GERMANY, ASSIGNOR TO WINTHROP CHEMICAL COMPANY, INC., OF NEW YORK, N. Y.

PROCESS FOR DISINFECTING HIDES, FELLS, SKINS, HAIRS, CATGUT, ETC.

No Drawing.

Application filed August 27, 1925. Serial No. 52,969.

The disinfection of fells, hides, skins, hairs, catgut, etc., is very difficult because heat, steam, alkalies and acids, or formaldehyde act in a deleterious manner upon the organic products.

I have found that halogenated amides, e. g. acetochloroamide, para-toluenesulfon-chloroamide (sodium salt) or mixtures of para-toluenesulfonamides with calcium hy-

10 pochlorite (chloride of lime) can profitably be used for this purpose. The disinfecting power of these ingredients is very strong, they penetrate well into the materials and are entirely harmless to them.

15 In order to illustrate my new process more fully, the following example is given:—

Example.—The dried hide of a guinea pig that died of anthrax is laid into a solution of the sodium salt of para-toluenesulfonchloroamide (1:300). After 10 hours the spores are killed. After tanning a good leather results.

In the same way catgut, etc. can be disinfected.

I claim:—

1. The herein described process for disinfecting hides, fells, skins, hairs, catgut, etc., which comprises treating these products with a solution of halogenated amides and removing the excess of liquid.

2. The herein described process for disinfecting hides, fells, skins, hairs, catgut, etc., which comprises treating these products with a mixture of chloride of lime and a sulfonamide and removing the excess of liquid.

3. The process for disinfecting hides, fells, skins, hairs, catgut, etc., which comprises treating these products with a solution of a sodium salt of para-toluenesulfonchloroamide.

In testimony whereof I have hereunto set my hand.

GEORG WESENBERG.
